LEVER CLOSING RING FOR CONTAINERS

Vivian D. Hornsby, Shaker Heights, Ohio, assignor to The F. C. Thornton Company, Cleveland, Ohio, a corporation of Ohio

Application November 20, 1957, Serial No. 697,690

6 Claims. (Cl. 292—256.69)

This invention relates to container sealing devices and more particularly it pertains to a lever closing ring for clamping in place the cover of a container such as a metal or fiber shipping drum.

Generally, shipping drums are open at one end and are usually provided with a peripheral bead. A removable cover for the open end is provided with a complementary peripheral flange for fitting over the bead in a substantially airtight manner. The cover flange is secured on the drum bead by a split ring of channel-shaped cross section that clamps the flange and bead together.

Prior clamping rings have included various means for contracting and expanding the ring. Most of the prior rings have been subject to several disadvantages having both structural and economic aspects. In some lever lock rings the lever moves in the plane of the ring either inside or outside of the ring circumference. One disadvantage of such construction has been that the levers prevent compact stacking of the shipping drums. Also, where the lever is movable within the circumference of the ring, it usually covers a portion of the surface of the cover and thereby reduces the area available for decoration, advertising, and the like.

Other prior lock rings have lever mechanisms movable in a plane perpendicular to that of the ring. Such mechanisms are usually complicated in nature with a considerable number of parts which are unduly costly.

Another disadvantage inherent in most lever lock rings is the tendency of the ends of the ring to gap open. One or both ends tend to spring out radially from alignment with each other and away from a desirable close fit on the cover and drum assembly. Such tendency ultimately may result in complete failure of the ring to lock the cover to the drum flange.

The device of the present invention includes a closing lever for a split lock ring having two end portions which are brought into closely aligned positions with respect to each other during the locking movement of the lever from the open position in a plane perpendicular to that of the ring to the closed position in the plane of the ring. One end of the lever is pivoted to one end of the ring and the other end of the ring is pivotally connected to a connecting link, the other end of which is pivotally attached to the lever. In the closed position all pivotal connections between the ring, the lever, and the link are in alignment with each other. In addition, the lever and link fit snugly against the outer periphery of the ring and the lever includes an offset intermediate portion enclosing the connecting link. One end of the offset intermediate portion of the lever is an inclined end wall which serves as a cam for directing one end of the ring into end-to-end alignment with the other end of the ring where it is retained by one end portion of the lever which fits snugly against the outer periphery of the ring.

Accordingly, it is an object of this invention to provide a lever closing ring for containers having the economic

2

advantages of minimum number of parts and minimum assembly costs.

It is another object of this invention to provide a lever closing ring for shipping drums having a lever movable in a plane perpendicular to the plane of the ring.

It is another object of this invention to provide a lever closing ring for metal or fiber shipping drums which provides an inclined camming surface for directing and holding opposite ends of the ring in close alignment in the locked position.

It is still another object of this invention to provide a lever closing ring for shipping drums in which the lever during the closing operation not only brings the split ring together into smaller clamping diameter while moving the ends into closely spaced aligned positions in the same plane, but also brings and holds one end of the ring in the same radial zone as that of the other end of the ring.

Finally, it is an object of this invention to provide an improved lever locking ring for containers which substantially eliminates the difficulties enumerated and which obtains the foregoing desiderata in a simple and effective manner.

These and other objects and advantages apparent to those skilled in the art from the following description and claims may be obtained, the stated results achieved and the described difficulties overcome by the discoveries, principles, apparatus, parts, combinations, subcombinations and elements which comprise the present invention, the nature of which is set forth in the following statement; preferred embodiments of which—illustrative of the best modes in which applicant has contemplated applying the principles—are set forth in the following description; and which are particularly and distinctly pointed out and set forth in the appended claims forming part hereof.

The improved lever closing ring construction of the present invention may be stated in general terms as including in a cylindrical, open head shipping drum having a closed bottom and an open top with a peripheral bead therearound, a cover for the open top having a peripheral flange engageable with the bead, a metal split ring surrounding the engaged flange and bead, the ring being substantially U-shaped in cross section, the ring having first and second end portions alignable in spaced relation when the ring is surrounding the engaged flange and bead, a locking lever having opposite end portions and an intermediate offset portion, one end portion of the lever being pivotally attached to one end portion of the ring with the intermediate offset portion outwardly spaced from the periphery of the ring, a connecting link having one end pivotally attached to the other end portion of the ring, the other end of the link being pivotally attached to the intermediate portion of the lever, the intermediate offset portion of the lever having a connecting inclined camming portion at an angle to the plane of the end portion pivoted to the first portion of the ring, the intermediate portion of the lever being substantially longer than the connecting link and forming a link receiving space with the ring, the lever being movable in a plane perpendicular to the plane of the ring between an open position and a closed position, the latter position being in the plane of the ring, the inclined portion of the lever providing a camming surface means for directing said other end portion of the ring snugly against the assembled flange and bead and in alignment with said other end portion when the lever is in the closed position, and the ring having an offset loop means for receiving the hooked end of the lever.

The preferred embodiments of the invention are illustrated, by way of example, in the accompanying drawings, wherein:

Figure 1 is a fragmentary elevational view of a lever closing ring in the closed position on a shipping drum;

Fig. 2 is a fragmentary elevational view of the device in the open position;

Fig. 3 is a fragmentary elevational view of the device in an intermediately closed position;

Fig. 4 is a plan view of the device in the intermediate position as shown in Fig. 3;

Fig. 5 is a horizontal sectional view taken on the line 5—5 of Fig. 1;

Fig. 6 is a vertical sectional view taken on the line 6—6 of Fig. 1;

Fig. 7 is a vertical sectional view taken on the line 7—7 of Fig. 5;

Fig. 8 is a vertical sectional view taken on the line 8—8 of Fig. 5;

Fig. 9 is a fragmentary elevational view of another embodiment of the drum and lever closing ring; and

Fig. 10 is an enlarged vertical sectional view taken on the line 10—10 of Fig. 9.

Similar numerals refer to similar parts throughout the several figures of the drawings.

Referring to Figs. 1 and 6, an open head barrel, container, or drum 1 includes a necked-in portion 2 and a rolled or curled bead 3 at the upper end thereof. A recessed cover or closure 4 fits into the necked-in portion 2 of the drum 1 and is provided at the upper end with a rounded flange 5 in which is seated an annular compressed gasket or sealing ring 6 for engagement with the upper side of the bead 3 of the drum 1.

The cover 4 is retained on the drum 1 by a closing ring 7 which is substantially U-shaped in transverse cross section and has an upper lip 8 and a lower lip 9. As shown in Fig. 6, the upper lip 8 engages the rounded flange 5 and the lower lip 9 engages the under portion of the bead 3 and the lips extend at an angle to each other so that upon tightening of the closing ring 7, the flange 5 is pressed against the bead 3 and the gasket 6 is compressed therebetween. As shown in Figs. 1—4, the closing ring 7 is split and includes ring end portions 10 and 11 which are separated to permit expansion of the ring to enable the lower lip 9 to clear the outer peripheries of the rounded flange 5 and bead 3, and which are brought together when the ring is closed in the position shown in Figs. 1 and 5.

The closing ring 7 has means for opening and closing including a handle lever 12 and a connecting link 13. The lever 12 is an elongated slightly arcuate member having opposite end portions 14 and 15 and intermediate portion 16, the latter of which is offset from the end portions 14 and 15 and outwardly from the closing ring 7. The intermediate portion 16 is connected to the end portions 14 and 15, respectively, by portions or segments 17 and 18 of the lever inclined at an angle to the end portion 15. The intermediate portion 16 forms a clearance 19 with the outer periphery of the ring 7 in which is disposed the connecting link 13 as shown in Fig. 5.

The lever 12 is pivotally connected to the end portion 11 of the ring 7 by a rivet 20 extending through the end portion 15 of the lever. The connecting link 13 is pivotally attached to the opposite end portion 10 of the ring 7 at one end by a rivet 21. The other end of the connecting link 13 is pivotally connected to the lever 12 at the intermediate portion thereof by a rivet 22.

Thus the closing ring 7 is provided with a closing device having only two operating parts including the handle lever 12 and the connecting link 13, and three rivets 20, 21, and 22. Moreover, minimum assembly costs are involved in that only six holes (two for each rivet) are punched in the parts and one loop is embossed in the ring.

The end portion 14 of the handle lever 12 is notched at 23 to provide a hook 24 at the end of the lever for engagement with a loop 25 embossed at the outer periphery of the ring 7. When the lever is rotated to

the closed position (Fig. 1), the hook 24 engages the loop 25 where it is retained against easy dislodgment by a boss 26 in the lower part of the hook as shown in Fig. 6. Moreover, a hole 27 is provided in the end portion 14 of the lever so that a sealing wire (not shown) may be attached to the loop.

The ring 7 is opened and closed by moving the handle lever 12 about the pivotal rivet 20 in a plane perpendicular to the plane of the ring. When the ring is closed by pushing down on the lever 12, the manual operation is relatively easy because the bottom of the drum is resting on a floor as compared with the type of lever that is moved for opening and closing in the plane of the ring.

When the lever 12 is fully raised or substantially so as shown in Fig. 2, the end portions 10 and 11 of the ring 7 are horizontally and vertically spaced from each other. In the raised position of the lever 12 the connecting link 13 holds the end portion 10 spaced from the end portion 11 both horizontally and vertically. In the open position the ring 7 may be stripped off or placed around the periphery of the assembly of the flange 5 and the bead 3. However, the ring 7 may be spread sufficiently to permit the inner end of the lower lip 9 to pass freely over the outer periphery of the rounded flange 5 of the cover 4.

When the ring is in place and ready for closing, the lever 12 is lowered from the position of Fig. 2 to that of Fig. 3. During that movement of the lever 12 the connecting link 13 moves the end portion 10 vertically and horizontally into closer alignment with the end portion 11 (Fig. 3). The downward rotational movement of the lever 12 moves the end portion 10 through the link 13 into closer and closer alignment with the end portion 11. In the final closed position of Fig. 1 the end portions 10 and 11 are in complete alignment with each other. The rivets 20, 21, and 22 are aligned, and the hook 24 engages the loop 25 as shown.

During the final movement of the lever handle 12 from the position of Fig. 3 to that of Fig. 1, the inclined portion 18 of the lever handle functions as a cam to move the end portion 10 of the ring 7 radially inward against the drum and cover assembly whereby it is brought into and retained in alignment with the end portion 11 in the closed position of the lever as shown in Fig. 5. In the closed position the end portions 10 and 11 of the closing ring 7 are preferably slightly spaced from each other and the outer surfaces of both end portions are in abutment with the inner surface of end portion 15 of the lever. The ends 10 and 11 of the ring are retained snugly in place against the assembly of the flange 5 and bead 3. So long as the lever 12 is maintained in the closed position of Figs. 1 and 5, there is no possibility of the end portions 10 and 11 of the ring moving outward from their tight contact with the flange 5 and bead 3. Accordingly, the ring 7 is held in place until the lever is again opened.

Another embodiment of the ring is shown at 28 in Figs. 9 and 10. The ring 28 is a substantially channel member having an upper leg 29 and a lower leg 30. The cross section of the ring 28 including the upper and lower legs 29 and 30 differs from that of the ring 7. The ring 7 is the usual type of ring used for steel drums like the drum 1. The closing ring 28, on the other hand, is the type of ring used for fiber drums 31 (Fig. 10), the upper end of which is necked-in at 32 and beaded at 33, which configuration is encased within a surrounding metal reinforcing member 34. The fiber drum 31 is provided with a cover or closure 35 having a flange 36 extending outwardly and downwardly around the bead 33 of the drum as shown in Fig. 10.

Moreover, the ring 28 is provided with a handle lever 37 and a connecting link 38 (similar to the handle 12 and link 13) which are attached to the ring 28 and to each other by similar rivets 39, 40, and 41. A hooked end 42

of the lever 37 engages a loop 43 in the ring in a manner similar to the hook 24 and loop 25, as described above.

The particular ring 28 having the upper and lower legs 29 and 30 is adapted to retain the particular cover 35 on the fiber drum 32. For that purpose the ring 28 includes a closing means identical with the closing means for the ring 7 which is particularly adapted for retaining the recessed cover or closure 4 on the steel open head drum 1.

The device of the present invention is an improvement over previous constructions because it provides an effective means for not only opening and closing the ring but also for holding the ends of the ring snugly against the periphery of the cover of the drum and in alignment with each other. For that purpose the closing ring includes a two-piece handle lever mechanism which is raised and lowered in a plane perpendicular to the plane of the cover between open and closed positions for expanding and contracting the ring. A minimum of parts is involved including a handle lever, a connecting link, and three rivets. Thus assembly costs are maintained at a minimum. Each of the ring, lever, link, and rivet parts are of simplest design.

More particularly, the ring closing mechanism is provided with an inclined cam surface. During the early stages of closing the ring the end portions thereof are moved in two directions horizontally and vertically into substantial alignment with each other. During the final closing stage of the lever, the inclined cam surface of the lever comes into contact with one of the open ends of the ring and moves it snugly against the periphery of the cover in precise alignment with the other end of the ring. In the final closing stage during said camming action the end portion of the ring is moved into the close fitting position in precise alignment with the other end of the ring against the normal outward thrust of the ring and away from the final closed position of the ring. Accordingly, the lever closing mechanism moves the ends of the split ring through three directions as compared to the prior constructions which move the ends through only two directions for closing. As a result, the problem of gapage between the ends of the ring is eliminated and thereby prevents the ring from causing slipping as in some prior constructions.

In the foregoing description certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction shown.

Having now described the features, constructions, and principles of the invention, the characteristics of the lever closing ring, and the advantageous, new and useful results provided; the new and useful discoveries, principles, parts, elements, combinations, subcombinations, structures and arrangements, and mechanical equivalents obvious to those skilled in the art are set forth in the appended claims.

I claim:

1. A lever closing ring device for a drum of the open head type having a peripheral bead provided with a drum cover having a bead engaging flange, the device including a split clamping ring having spaced ends and having a U-shaped transverse cross section engageable with said flange and bead when the latter are assembled, means for expanding and contracting the ring including a lever pivotally connected to the ring near one of said ends, a connecting link pivoted to the ring near said other end, the connecting link also being pivoted to the lever, and the lever having inclined surface means radially facing the ring engaging and pressing said other end of the ring

radially inwardly against said assembled flange and bead during ring contracting movement of the lever.

2. A lever closing ring device for a drum of the open head type having a peripheral bead provided with a drum cover having a bead engaging flange, the device including a split clamping ring having spaced ends and having a U-shaped transverse cross section engageable with said flange and bead when the latter are assembled, means for expanding and contracting the ring including a lever movable in a plane perpendicular to the plane of the ring between open and closed positions corresponding to expanded and contracted positions of the ring, the closed position of the lever being in the plane of the ring, the lever being pivotally connected to the ring near one of said ends, a connecting link pivoted to said other end of the ring, the connecting link also being pivoted at its other end to the lever, and the lever having inclined surface means radially facing the ring engaging and pressing said other end of the ring radially inwardly against said assembled flange and bead during ring contracting movement of the lever.

3. A lever closing ring device for a drum of the open head type having a peripheral bead provided with a drum cover having a bead engaging flange, the device including a split clamping ring having spaced first and second ends and having a U-shaped transverse cross section engageable with said flange and bead when the latter are assembled, means for expanding and contracting the ring including a lever movable in a plane perpendicular to the plane of the ring between open and closed positions corresponding to expanded and contracted positions of the ring, the closed position of the lever being in the plane of the ring, the lever having lever end portions and an intermediate portion, the intermediate portion being offset from and connected to at least one end portion by an inclined lever portion radially engaging and pressing said first end of the ring radially inwardly against said assembled flange and bead during ring contracting movement of the lever, the lever being pivotally connected at the lever end portion adjacent the inclined lever portion to the ring near the second end of the ring, a connecting link pivoted to the ring near the first end of the ring, the connecting link also being pivoted to the intermediate portion of the lever, and the intermediate portion of the lever providing a clearance space adjacent the ring in which the connecting link is disposed when the lever is in closed position.

4. The construction as set forth in claim 3 in which the ring and lever are provided with complementary means for latching the lever in closed position.

5. A lever closing ring device for a drum of the open head type having a peripheral bead provided with a drum cover having a bead engaging flange, the device including a split clamping ring having spaced first and second end portions and having a U-shaped transverse cross section engageable with said flange and bead when the latter are assembled, means for expanding and contracting the ring including a lever movable in a plane perpendicular to the plane of the ring between open and closed positions corresponding to expanded and contracted positions of the ring, the closed position of the lever being in the plane of the ring, complementary means including a hook on the lever and an integral hook engaging loop in the ring for latching the lever in closed position, the lever having first and second end portions and an intermediate portion therebetween, the intermediate portion being offset from said lever end portions, the first lever end portion being pivotally connected to the first ring end portion, a connecting link pivotally connected at one end to the second end portion of the ring, the connecting link being pivotally connected at its other end to the intermediate portion of the lever, the lever having an inclined camming portion between the first end portion and the intermediate portion and radially facing the ring, the inclined camming portion of the lever being radially

engageable with the second end portion of the ring during the movement of the lever from open to closed positions, the first end portion of the lever overlapping the spaced first and second end portions of the ring when the lever is in closed position, and the intermediate portion of the lever providing a clearance space for the connecting link when the lever is in closed position.

6. A lever closing ring device for a drum of the open head type having a peripheral bead provided with a drum cover having a bead engaging flange, the device including a split clamping ring having spaced ends and having circumferentially-extending spaced inturned flanges engageable with said cover flange and drum bead when the latter are assembled, means for expanding and contracting the ring including a lever movable in a plane perpendicular to the plane of the ring between open and closed positions corresponding to expanded and contracted positions of the ring, a connecting link, a pivotal connection between one end of the lever and one end of the ring, a pivotal connection between one end of the link and the

other end of the ring, a pivotal connection between the other end of the link and an intermediate portion of the lever, the axes of said pivotal connections being in the same plane when the lever is in closed position, said plane containing said closed-position-pivotal-connections lying intermediate the circumferentially-extending spaced inturned ring flanges and perpendicular to the plane in which the lever is movable, and the lever having inclined surface means radially facing the ring engaging and pressing the end of the ring opposite that to which the lever is pivotally connected radially inwardly against said assembled flange and bead during ring contracting movement of the lever.
